A. & J. KRAUSS.

Fertilizer.

Patented Oct. 16, 1830.

John and Jacob Knapp (of Upper Mifflin Township, County of Leigh, State of Pennsylvania) have made an improvement, being a machine for spreading lime, plaster &c on Land.

It is believed to be formed from the Patent and making part of the same, containing a description in the words of the said Inventors, -
Jacob & John Knapp, the name of their improvement, being a machine for spreading lime, plaster &c on Land.

It is known that we, John Knapp, and Jacob Knapp of Upper Mifflin Township, County of Leigh, State of Pennsylvania, have made an improvement, being a machine for spreading lime, plaster &c on Land, & that the following is a description of the same.

This machine consists of the following principal parts viz. 1st The Wagon body 2^d The axle tree & wheels 3^r The frame 4th The Roller 5th The Valley. 1st The Wagon Body is made similar to those in common use, except that its bottom does not extend the whole length length of the wagon body, but only as far as the upper surface of the roller, (hereafter to be described) & within about 2¹/₂ inches of the bottom of the back board, leaving a space or opening through which the lime &c passes, of about 2 inches; A piece of leather nearly the length of the roller, & about 1¹/₂ inches wide, is nailed to the end of the wagon bottom, & projects beyond it on the roller about $\frac{3}{4}$ of an inch. The tail board moves up and down in grooves cut on the sides of the wagon body. The wagon body is wider at the hinder than at the forward end, & meets with its forward end on the front axle tree, its hinder end on the frame hereafter to be described. In making lime or plaster having a middle must be used & separate them. 2^d The axle tree & wheels.

This is made from 4 wheels. The forward axle tree & wheels are to be the same as working on it as usual, but the wheels of the hinder axle tree, do not turn on it, & are forced on the axle tree mounted within the frame in such a manner as to turn in the side pieces thereof. On one end of this last axle tree, & also on the middle of the frame is a pulley.

3rd. The frame is made by forming together two side pieces joined by mortises & tenons, forming a frame a little more than half as long as the wagon, & a few inches wider than the width of the wagon body. It is placed under the wagon body at the hinder end, and connects the hinder wheel with the axle as before mentioned. It is attached to the forward side by a connecting piece of timber with iron bolts.

4th. The Roller is in length equal to the width of the frame within which it revolves, & about 8 inches diameter. It turns on guides on metal boxes in the side pieces of the frame. One of the guides projects beyond the outer side of the frame on which is a pulley. The roller is placed near the hinder end of the frame, with its upper surface directly below the opening for the passing of the lime & it almost touching the end of the bottom of the wagon. It is by the revolving of this roller that the operation of spreading the lime &c is performed.

5th. The Pulley consists in number two placed one on the side of the hinder axle tree, and the other on the end of the wagon of the roller as before mentioned. The pulley on the axle tree is 16 inches in diameter, the other on the roller is 15 inches in diameter. Around both passes a iron chain which is crossed. Instead of this gearing, cog-wheels may be substituted.

Operation

The horses or other animals being attached to the manuring wagon in any convenient manner & the wagon filled with lime or plaster to be drawn forward, causes the wheels, pulley & roller to revolve the roller being in contact with the lime or plaster, draws it gradually from the wagon & spreads it evenly over the surface of the earth as the wagon advances. What we claim as our invention and which we wish to secure by Letters Patent is the machine, as above described, for spreading lime, plaster &c on Land. For the better to illustrate our invention we refer to the model or drawing of the same, deposited in the patent office.

In witness whereof we the undersigned
do sign our names before this 20th day of November, 1840.

Leavenworth County, first day of September A.D. 1920.
